US0D1003309S

(12) **United States Design Patent** (10) Patent No.: **US D1,003,309 S**
(45) Date of Patent: ** Oct. 31, 2023

(54) **ELECTRONIC DEVICE WITH GRAPHICAL USER INTERFACE**

(71) Applicant: **Apple Inc.**, Cupertino, CA (US)

(72) Inventors: **Taylor Gerard Carrigan**, San Francisco, CA (US); **Alan C. Dye**, San Francisco, CA (US); **Charmian Naguit**, San Francisco, CA (US)

(73) Assignee: **Apple Inc.**, Cupertino, CA (US)

(**) Term: **15 Years**

(21) Appl. No.: **29/782,897**

(22) Filed: **May 10, 2021**
